UNITED STATES PATENT OFFICE.

DONALD W. ROSS, OF JOLIET, ILLINOIS.

MILK-STRAINER.

1,390,815.

Specification of Letters Patent. Patented Sept. 13, 1921.

Application filed September 30, 1920. Serial No. 413,769.

To all whom it may concern:

Be it known that I, DONALD W. Ross, a citizen of the United States, residing at Joliet, in the county of Will, State of Illinois, have invented certain new and useful Improvements in Milk-Strainers, and I do hereby declare the following to be a full, clear, and exact description of the invention, such as will enable others skilled in the art 10 to which it appertains to make and use the same.

This invention relates to new and useful improvements in milk strainers and particularly to holding devices for milk strainers.

15 One object of the invention is to provide a holder for a cloth strainer which can be more easily and quickly applied to the funnel and removed therefrom than with similar devices heretofore.

20 Another object is to provide a means for holding the lower pointed end of the strainer which can be more quickly and easily engaged and disengaged than similar devices heretofore.

25 Other objects and advantages will be apparent from the following description when taken in connection with the accompanying drawing.

In the drawing:

30 Figure 1 is a top plan view of a funnel in which my improved strainer holder is disposed.

Fig. 2 is a vertical longitudinal central sectional view through the device taken on 35 the line 2—2 of Fig. 1.

Fig. 3 is a bottom plan view of the funnel, showing the lower end of the strainer cloth held by the wire loop of the funnel.

Fig. 4 is an elevation of the upper portion 40 of the funnel showing the strainer holding ring.

Referring particularly to the accompanying drawing 10 represents the metal funnel which is adapted to be inserted in the mouth 45 of a milk can. In the bottom, or smaller end of the funnel there is secured a transversely extending wire 11, the intermediate portion of which is formed with an upwardly extending loop 12, said loop being 50 wedge-shaped, with the narrow entrance throat 12'.

The cloth 13 is placed over the mouth of the funnel, and the center pushed down thereinto, a small ball 14 being placed in the 55 center of the cloth. The center of the cloth, with the ball therein, is then pressed through

the throat 12' and into the loop 12. The margin of the cloth is then drawn across the upper or mouth end of the funnel until the cloth is stretched tight. A split band 15 is 60 then slipped onto the mouth of the funnel, outwardly of the cloth margin and pushed down to firmly clamp the cloth against the funnel. The lower edge of this band 15 is flared outwardly, as at 16, to permit a more 65 easy engagement on the cloth and funnel, while the upper edge of the band is formed with an inwardly directed circumferential flange 17, which rests on the cloth and upper edge of the mouth of the funnel to prevent the band from being pushed down too 70 far. The ends of the band are normally out of contact with each other, even when engaged around the cloth and funnel, and in each end of the band there is formed a 75 struck out loop 18 which receives one end of a wire 19. This wire 19 is formed, intermediate its ends, with a series of waves or kinks, shown at 20, which render the wire resilient to normally urge the ends of the 80 band toward each other, and thus firmly embrace the mouth of the funnel and the cloth.

It will be noted that the wire 11 is stationary in the lower end of the funnel, and is 85 in such a position therein that the fingers of the operator can be easily inserted in the lower end of the funnel to grasp the ball and inclosing portion of the strainer cloth, to engage or disengage the same with respect 90 to the wire loop 12.

Surrounding the intermediate portion of the funnel is an outwardly and downwardly inclined flanged ring 21 which overlies the mouth of the milk can and thus effectively 95 prevents the entrance of dirt and other foreign substances into the can. This ring may be formed integrally with the funnel or removable, or may be secured thereto by soldering.

100 By this construction the strainer cloth can be more easily and conveniently wrung to squeeze the milk therefrom, and without the annoyance of twisting or tangling of cords or wires, as in previously patented devices.

What is claimed is:

1. In a milk strainer the combination with a cloth having a spherical object in the center thereof, of a funnel having a transverse member in the smaller end formed with a 110 loop for the reception of said cloth center and spherical object, and detachable and re-

silent means for engagement with the margin of the cloth and the mouth of the funnel.

2. A means for retaining the center of a cloth milk strainer in which is disposed a spherical object comprising a funnel and a wire secured in the smaller end of the funnel and extending transversely thereacross, the intermediate portion of the wire being formed with an upwardly directed wedge

loop having a narrow entrance throat 10 through which the portion of the cloth above the spherical member is wedged.

In testimony whereof I affix my signature in the presence of two witnesses.

DONALD W. ROSS.

Witnesses:

LOR D. Ross,
KATHERINE J. Ross.
